MARINE TYPE DRAFT ADJUSTER

Arthur J. Ward, Washington, D. C.

Application June 28, 1945, Serial No. 602,142

8 Claims. (Cl. 236—45)

(Granted under the act of March 3, 1883, as amended April 30, 1928; 370 O. G. 757)

1

This invention relates to a marine type draft adjuster with automatically self-adjusting parts.

The present improvement will be described in connection with conventional oil burning galley range and bake oven assemblies aboard ship. It provides a means for maintaining a predetermined draft regardless of inside and outside pressures on the adjuster or of the ship's pitching and rolling motions. As will be understood, pitch refers to longitudinal rising and falling motion of vessels whereas roll refers to the transverse motions. The outside pressures on the adjuster damper will of course be changed by the opening of galley doors and the like and the damper responds automatically to these changes.

Prior draft adjusters, while reasonably satisfactory for shore installations, are all characterized by being adversely affected by the ship's motion. For example, in rough weather a ship may roll 45° and more. Under these conditions the pressure responsive dampers of prior adjusters will swing in response to motion as well as pressure, and hence give a fluctuating draft. This renders the usual pressure calibration completely inaccurate and ineffective.

The present invention overcomes these difficulties by constantly maintaining the predetermined amount of draft. This result is accomplished by a system of pivots, counter weights and anti-friction bearings. The device includes a cylindrical member for making a stovepipe connection with the conventional smokepipe. A pair of brackets extend longitudinally of the member and provide pivots for the adjuster unit. The body or housing of the unit is counterweighted on the pivots regardless of the ship's motion. A flexible flameproof or fireproof fabric covers the portion between the unit and the cylindrical connection to permit response to the action of the counterweight.

The adjuster body is conveniently a sheet metal housing and contains a counterweighted draft adjusting damper which is calibrated in a known manner. In short, the position and size of the weight determines the damper opening and the effective draft pressure. The damper is pivotally mounted at opposite sides in the novel weighted frame member which rides on a ball or roller bearing race.

The combination of the anti-friction bearings and weights insures a position substantially vertical to the earth's center at all times. It will be seen that this construction avoids irregular bearing pressures on the damper pivots and maintains the calibration of the damper without in-

terference by either the pitch or roll of the vessel. It permits response to pressures and operating conditions in substantially the same manner as in a shore installation.

An object of the invention is to provide a marine type draft adjuster unit which will be self compensating for the pitch and roll of a vessel.

Another object is to provide a draft adjuster with a system of pivots, weights and anti-friction bearings which will maintain the adjuster damper support in vertical position during a rough sea.

These and other objects of invention will be manifest from a consideration of the following description, claims and drawings in which:

Fig. 1 is a schematic view of a galley bake oven and range assembly including the improved unit joined to the smokepipe.

Fig. 2 is a side elevation of the improved unit.

Fig. 3 is a front view of the improved unit.

20 Referring to the drawing, Fig. 1 shows galley ranges 10, 11 and bake oven 12, all conventionally connected to smokepipe 13. The improved draft control adjuster is attached at one end of the smokepipe 13 as shown. It consists of a cylindrical connection member 14 on which brackets 15 and 16 are secured as by rivets 17. The brackets 15 and 16 carry pintles as at 18 on which the draft adjuster housing pivots. A fireproof or flameproof fabric 21 cemented and riveted to member 14 and housing 20 provides a flexible draft passage. The fabric 21 is closely woven or fabricated and treated to make it substantially airproof. A circular member 22, L-shaped in cross section, and ring 23 when fitted and secured together maintain the ball bearing race 24 in position to support the adjuster frame 25 counterweighted at 26. The counterweight 26 will always assume the lowermost position regardless of pitch or roll. Adjuster frame 25 supports pintles 27 and 28 for the calibrated pressure responsive damper 29 with conventional calibrated weight 30.

45 The damper housing 20 is counterweighted at its sides to compensate for the weight of the damper race and weight. These counterweights 31 and 32 are screw threaded on brackets 33 and 34 so as to cause the center of gravity of the unit to be just below the pivot points 18 and 19. This will permit pivotal movement and cause the adjuster housing to remain upright substantially along the vertical.

50 It will be seen that I have compensated both for pitch and for roll in vessels. The present improvements are obviously adapted for use on

trains, aircraft or other installations subject to similar motions.

This invention may be made or used by or for the Government of the United States for governmental purposes without the payment to me of any royalties thereon or therefor.

What I claim is:

1. In a draft adjuster, a smoke pipe conductor, a circular damper housing pivotally mounted on said connector, a circular anti-friction race positioned in that housing, a self-adjusting weighted member rotatably mounted on said anti-friction race and a pressure responsive damper member movably supported on said weighted member. 10

2. In a draft adjuster, a smoke pipe connector, a circular damper housing pivotally mounted on said connector, a circular anti-friction race secured in the housing, a self adjusting weighted member rotatably mounted on said anti-friction race and a pressure responsive calibrated damper member pivotally supported on said weighted member. 15

3. In a draft adjuster, a smoke pipe connector, a damper housing pivotally mounted to said connector, said pivoted damper housing having its center of gravity below the pivot axis, an anti-friction race positioned in the housing, a self adjusting weighted member rotatably mounted on said anti-friction race and a pressure responsive damper member pivotally supported on said 20 weighted member.

4. In a draft adjuster, a smokepipe connector member, a support means on said connector member, a pivoted damper housing on the support means, an anti-friction race secured to the housing, a self adjusting weighted member rotatably mounted on said race and a pressure responsive draft control member supported on said weighted member. 25

5. In a draft adjuster, a smokepipe connector member, a support means on said connector member, a pivoted damper housing on the support means and a flexible connection forming an air passage between the smokepipe connection member and the housing. 30

6. In a draft adjuster, a smokepipe connector member, a support means on said connector member, a pivoted damper housing on the support 35

means, a flexible connection between the said connector member and housing, a counterweight on the housing, an anti-friction race positioned in the housing, a self adjusting weighted member rotatably mounted on said race and a pressure responsive draft control member pivotally supported on said weighted member. 40

7. In a draft adjuster for use on a ship, a pivoted circular damper housing, a circular ball bearing anti-friction race, a weighted self-adjusting rotatable circular damper frame, a connector pipe, a flexible air-tight fabric connection, an adjustable counterweight on the pivoted circular damper housing and a counterweight on the weighted self-adjusting rotatable circular damper frame to insure the weighted self-adjusting rotatable circular damper frame holding the pivoted calibrated pressure responsive circular damper in an upright or operating position regardless of the pitch or roll of the ship. 45

8. In a draft adjuster, a pivoted circular damper housing, a circular ball bearing anti-friction race, a weighted self-adjusting rotatable circular damper frame, a connector pipe, a flexible air-tight fabric connection, an adjustable counterweight on the pivoted circular damper housing, a counterweight on the weighted self-adjusting rotatable circular damper frame and two supports between the connector pipe and the pivoted circular damper housing which are rigidly fastened to the connector pipe and pivotally fastened to the pivoted circular damper housing. 50

Patent No. 2,521,764

September 12, 1950

ARTHUR J. WARD

It is hereby certified that error appears in the printed specification of the above numbered patent requiring correction as follows:

Column 3, line 8, for the word "conductor" read *connector*;
and that the said Letters Patent should be read as corrected above, so that the same may conform to the record of the case in the Patent Office.

Signed and sealed this 28th day of November, A. D. 1950.
